C. J. REIGH

ELECTRIC SIGNAL LAMP FOR RAILWAY SWITCHES

Filed Sept. 24, 1925

FIG. 1.

FIG. 4.

Inventor
C. J. Reigh
By
Murphy, Jr.
Attorney

UNITED STATES PATENT OFFICE.

CLARENCE J. REIGH, OF ALTOONA, PENNSYLVANIA.

ELECTRIC SIGNAL LAMP FOR RAILWAY SWITCHES.

Application filed September 24, 1925. Serial No. 58,390.

To all whom it may concern:

Be it known that I, CLARENCE J. REIGH, a citizen of the United States, residing at Altoona, in the county of Blair and State 5 of Pennsylvania, have invented certain new and useful Improvements in Electric Signal Lamps for Railway Switches; and I do hereby declare the following to be a full, clear, and exact description of the invention, such 10 as will enable others skilled in the art to which it appertains to make and use the same.

This invention relates to an electric signal lamp for railway switches.

15 The prime object is to provide a novel construction wherein the present signal lamp and mounting may be used; together with the lamp frame or casing, so as to readily, inexpensively and expeditiously 20 adapt the main parts of a present signal lamp supporting and operating structure to the practice of the present invention.

Another object is to provide a structure using a novel bracket substantially in the 25 form of a yoke attachable at one end to the lamp and at the other end to the stem, and having its bridge vertical and offset.

The more specific objects and advantages 30 will become apparent from a consideration of the description following taken in connection with accompanying drawings illustrating an operative embodiment.

In said drawings:—

35 Figure 1 is a view showing the invention in front elevation;

Figure 2 is a sectional view taken on the line 2—2 of Figure 1;

40 Figure 3 is a sectional view taken on the line 3—3 of Figure 1;

Figure 4 is a sectional view taken on the line 4—4 of Figure 1; and

Figure 5 is a detail perspective view of a modified form of lamp-carrying bracket which may be used.

45 Referring specifically to the drawings, a tie or other support is shown at 10 for a stem 11 disposed in upstanding relation thereto and journaled in a suitable bearing comprising a plate 12 and bracket 12^a secured thereto. These parts form the usual construction of a railway switch signal lamp operating means. The stem 11 has the usual opening 13 in which the operating parts are connected in the usual manner in order to rock or turn the stem.

In carrying out the present invention, a bracket is provided as at 14, being a yoke or U-shaped, having its bridge 15 vertically disposed and offset at one side of the plane of the stem 11 and having one of its arms in 60 the form of a split clamp 16 adapted to be tightened by a bolt 17 about a polygonal or other portion 18 of the stem 11, above the uppermost bearing 12^a. The other arm 17 constitutes an attaching plate for the signal lamp shown at 18. This lamp or lamp casing 18 is of usual construction and is bolted or otherwise removably secured as at 19 to the arm or plate 17.

In the present instance, in lieu of the use 70 of oil to illuminate the lamp, an electric bulb 19 is disposed within the lamp and is carried by a pipe or conduit 20, which is stationary and extends up into the casing 18 at the vertical center thereof. The conduit 20 is irregular to adapt it to its surrounding and wires from a suitable source of electricity pass through the conduit to the lamp 19 in order to illuminate the same. It 75 will be realized that as the pipe or conduit 40 is stationary, the lamp 18 is adapted to turn relatively thereto with the bracket 14 and that the offset 15 permits the necessary movement of the lamp irrespective of the 80 adjacency or location of the pipe or conduit 20.

In using the invention, it will be realized 85 that the ordinary lamp is used, minus its wick and means of oil supply, that such lamp may be secured in place by the bracket 14 and that the light is supplied by the bulb 19.

If desired the bracket 14 may be made 90 from a single bar of metal appropriately bent into shape and for instance like the bracket 21 shown in the modified form of Figure 5. Such bracket has an attaching arm 22 adapted for connection in any suitable manner rigidly to the stem 11 and having a plate or arm 23 adapted for connection 95 to the lamp casing 18 and also having an opening 24 therethrough to accommodate the pipe or conduit 20.

100 Various changes may be resorted to provided they fall within the spirit and scope 105 of the invention.

I claim as my invention:—

1. In combination with a switch-operated stem, a bracket secured thereto, a signal lamp carried by the bracket, and stationary 110 means extending to the lamp to form a con-

duit for electric wires for the illuminating means of the lamp.

2. In combination with a stem operated by a switch, a bracket attachable to the stem, a signal lamp carried by the bracket, said bracket having an offset portion, a conduit extending to the lamp and adapted as a means for passage of conductors there-through to the illuminating means of the lamp.

3. In combination with a stem operable by a switch, a bracket having a portion attach-

able to said stem and having an arm, a lamp carried by said arm, a conduit extending through said arm and into said lamp at 15 a portion thereof coaxial with said stem, said conduit being adapted to accommodate electric wires for the illuminating means of the lamp, and the bridge of said bracket being offset with respect to said portion. 20

In testimony whereof I affix my signature.

CLARENCE J. REIGH.
